UNITED STATES PATENT OFFICE.

PAUL S. GRIERSON, OF SOUTH ORANGE, NEW JERSEY, ASSIGNOR TO CHARLES CORY & SON, INCORPORATED, OF NEW YORK, N. Y., A CORPORATION OF NEW YORK.

GENERAL-ALARM SYSTEM FOR BATTLESHIPS.

Application filed September 21, 1921. Serial No. 502,238.

This invention relates to a signalling system and more particularly to a general alarm system intended to be used on battleships; and has special reference to the provision of a system of this type in which any of a plurality of distinctive signals or alarms operated from a central ship station may be efficiently selected and controlled from any of a plurality of outlying ship stations.

In general alarm systems of the type referred to such as, for example, the system disclosed in the patent to Wood, No. 1,220,484, dated March 27th, 1917, a number of signalling means preferably taking the form of alarm elements such as gongs are scattered in various parts of the ship, the alarm elements being operated from a central station which is controlled from any of a plurality of outlying stations such as the bridge, quarterdeck or conning tower of the vessel. In these systems manipulation of any of the control elements at the outlying stations puts into activity provisions at the central station for operating the alarm elements for a predetermined period of time, such as, for example, one minute, the alarm being automatically discontinued at the end of such period.

In prior general alarm systems of this kind manipulation of any of the control elements at the outlying stations would start the system operating for delivering or rendering only one character of signal, the system thus being relatively non-flexible and limited in use. A prime desideratum of my present invention contemplates the provision of an improved general alarm system in which the alarm elements may be made to render or deliver any of a number of distinctive signals selected at the will of the operator or officer in charge at any of the outlying control stations, thus yielding a system of desired increased flexibility and of wider utility.

In prior systems of the kind hereinabove mentioned it was necessary, in order to set the central station provisions operating for the desired predetermined period, to exercise control of the outlying station elements for a somewhat extended period of time of, say, from five to ten seconds, this for the reason that the continued operation of the said central station provisions depended upon its being brought into full activity. My present invention contemplates an improvement

over these prior systems in the provision of means whereby the system can be set into operation and into continued operation instantly, thus eliminating the time factor previously found necessary in manipulating the outlying station control elements.

In the systems in prior use, after setting the central station provisions into activity, the signals were kept operating for the full predetermined period, irrespective of the desire of the officer to continue or discontinue signalling operation; in my present invention the control elements may be manipulated at will by the officer to stop the sounding of the alarm or to change the character of the signal during the predetermined period of operation of the central station provisions.

The principal objects of my invention may therefore be said to include, besides the provision of a general alarm system in which any of a variety of distinctive signals set into operation for a predetermined period of time may be controlled from any of a plurality of stations, the provision of an alarm system in which the signals may be set instantly into operation and into continued operation for the predetermined period, the provision of an alarm system in which the signals may be stopped or changed at will during the said predetermined period, the further provision of a system of this nature in which, after the outlying station control elements have been manipulated to set the system into activity, it is unnecessary to return the elements to initial or "off" position, thus rendering the device "fool-proof" and eliminating the "human equation"; the still further provision of an alarm system of this nature in which, when the system is being operated from one control station, the system is under absolute control from such station, the other stations being automatically locked out, this preventing interfering signals from a plurality of stations to be rendered at the same time and the final provision of an alarm system, its central station provisions and its outlying or remote station elements in which the parts are few in number, are co-related in a simple manner, are easily accessible and are manipulable in a facile manner.

To the accomplishment of the foregoing and such other objects as may hereinafter appear, my invention consists in the ele-

ments and their relation one to the other, as hereinafter particularly described and sought to be defined in the claims, reference being had to the accompanying drawings which show a preferred embodiment of my invention, and in which:

Figure 1 is a diagrammatic view of my system showing the signalling elements, the central operation station and the plurality of outlying stations with the wiring connections therebetween.

Figure 2 is a view of the panel at the central control station with operating provisions thereon,

15 Figures 3 and 4 are views of details of said provisions,

Figure 5 is a plan elevational view of a transmitter mechanism employed at the out-lying stations, the cover of said mechanism being removed, and

Figure 6 is a central cross sectional elevational view of the same.

Referring to Figure 1 of the drawings, the invention comprises a general alarm system in which a number of signalling elements in the form of single stroke gongs g are scattered in various locations of the ship, the said gongs being operated in a predetermined manner from a central control panel P , the panel P being controlled from any of a plurality of stations such as the bridge, quarterdeck or conning tower of the vessel by means of transmitter mechanisms such as T , T_1 and T_2 located respectively at stations designated 1, 2 and 3 in Figure 1 of the drawings.

On the central control panel P are provisions intended to be actuated for operating the gongs g in a variety of ways to produce any of a plurality of distinctive signals selected at will. For operating the signalling means I provide the motor M having the shunt wound field R and the variable resistance r , the latter being provided for the purpose of governing the speed of the motor, the said motor being connected by a line of shafting designated by s and connected to a series of make and break timing wheels a , b , c , d and e respectively, a motor control timing wheel f being also provided and operated by the motor M for controlling the stopping of the motor, as will appear more in detail hereinafter. The panel P is further provided with a solenoid S, the said solenoid being adapted to be energized by make and break circuits operated by the timing wheels a , b , c , d and e respectively, to sound the gongs g to produce any of a plurality of distinctive signals.

The operating provisions for sounding the gongs *g*, which in the present exemplification of my invention preferably take the form of the timing wheels *a*, *b*, *c*, *d* and *e*, are intended to be actuated for a predeter-

mined period, such as one minute, the operation of these provisions being controlled from any of the outlying stations 1, 2 or 3. The setting of these provisions into operation is controlled by means of the hand operated switch devices 10, 11 and 12, located at the outlying stations and preferably forming part of the transmitters T, T₁ and T₂, the said switch devices being normally open and being intended to be closed for starting the motor M and actuating the timing wheels *a* to *e* inclusive. The switches 10, 11 and 12 are arranged in parallel, manipulation of each of these switches effecting motor operation. The circuits including the switches 10, 11 and 12 are therefore similar and the tracing of one of these circuits will suffice to show the control of the panel from any of the outlying stations. From the positive side of the main line 13 the circuit may be traced through the conductor 14, through the switch 15, through the conductor 16 to a terminal 17, thence through the conductor 18 to the terminal designated as 19 and thence by way of the conductor 20 to the line 21, then to the branch conductor 22 which leads to the multiple switch 23, the current then passing from the switch to the conductor 24 and thence to the manually manipulable switch 10 at station 1, the current passing from this switch when closed to the conductor 25, back to another terminal of the multiple switch 23 and from said terminal by way of a lead 26 to one pole of the electromagnet 27 and through the said electromagnet, the conductor 28 connecting the other terminal of said electromagnet to the conductor 29 connected to the wire 30, the said wire 30 being in turn connected to the motor M, the current passing from the motor to the return conductor 31 which is connected to the terminal 32, a conductor 33 connecting said terminal to the negative end of the main line 34 by means of the connecting lead 35 and the switch 15. From this wiring diagram it will be seen that closing the switch 10 will close the motor circuit, setting the same into operation for causing the actuation or rotation of the provisions *a* to *f* inclusive. As hereinbefore indicated, the motor may be similarly controlled from switches 11 and 12 and to this end these switches are arranged in parallel across the lines 20 and 29 by means of conductors 24₁ and 25₁ and 24₂ and 25₂, the multiple switches 23₁ and 23₂, leads 26₁ and 26₂ and electromagnets 27₁ and 27₂.

As hereinbefore indicated, a desideratum of the present invention comprehends the provision of a system in which the motor M 125 may be set into activity and in which the said activity may be caused to continue for a predetermined time instantly upon the manipulation of the controlling switches 10, 11 or 12, it being unnecessary to continue ma- 133

nipulation of such switches for any extended period of time, as has been the case in prior devices. To accomplish this end the electromagnets 27, 27₁ and 27₂ referred to above are provided, these electromagnets, as pointed out, being in series with the controlling switches and the motor M, these electromagnets being provided for the purpose of closing the motor circuit by automatic switch means and for keeping the said motor circuit closed when the hand operated switches 10, 11 or 12 are released. Referring to the electromagnet 27, energization of this electromagnet will attract an armature 36, the said armature being provided with a button 37 adapted for cooperation with spring contact arms 38 and 39 to spread these contact arms apart for closing independent circuits when brought into contact with the top and bottom spring arms 40 and 41 respectively. The spring contact arms 38 and 39 are connected by means of lead 42 to the conductor 22, the contact arm 41 being in turn connected to the lead 26. From this construction it will be seen that when the armature 36 is drawn by the energized magnet 27, the motor circuit will be closed between the contact arms 38 and 41, thus short circuiting the manually controlled switch 10, continued energization of the electromagnet 27 effecting the continued closing of the motor circuit through this automatic contact switching means, irrespective of the release of the switch 10, the motor being thus brought into instant operation and being kept in operation upon immediate release of the switch 10. In a similar manner the electromagnets 27₁ and 27₂ control the automatic switches at station 2 and station 3 for closing the motor circuit from said station and short circuiting the control from the switches 11 and 12 respectively.

In the present exemplification of my invention the motor M, after being set in operation, is continued in operation for a predetermined period of time such as one minute, stopping of the motor after the predetermined period being automatically effected by means operated from the motor. To effect the stopping of a motor after the desired period the timing wheel f referred to above is provided, the said timing wheel being operated from the motor by being connected to the shafting s, as hereinbefore indicated. The driving parts are so proportioned that the timing wheel f is rotated at substantially 1 R. P. M. The timing wheel f is provided with a button 43 adapted in the rotation of the timing wheel f for engaging and moving a spring contact arm 44 for cooperation with a complementary spring contact arm 45, the said contact arms being connected across the conductors 29 and 20 respectively, the said conductors leading, as hereinbefore pointed out, to the electromagnets 27, 27₁ and 27₂.

From this construction it will be seen that, after the timing wheel f has received a complete revolution for the duration of one minute, the spring contact arms 44 and 45 will be caused to engage with each other for momentarily closing the motor circuit and for short circuiting the electromagnets 27, 27₁ or 27₂. As will be understood, the short circuiting of the electromagnets will release the armatures controlled thereby for opening the automatic switches at the outlying stations, the continued rotation of the timing wheel f opening the motor circuit by releasing the switch arm 44, the motor circuit thus being opened at all points, this in turn effecting the retardation and stopping of the motor itself.

It is desired that when the motor is set into activity from any one station, such as station 1, that the motor be absolutely controlled from such station and that the remaining stations be locked out in order to prevent conflicting signals from being transmitted to the gongs g. To this end the resistances of the electromagnets and motor are so predetermined as to yield a current of such a predetermined amount in the motor circuit to permit control from only one station and to prevent control from two stations at the same time. Thus, for example, .2 of an ampere may be decided upon for the motor circuit, this amperage being just sufficient in electromagnet energization for attracting the armature 36, less current being insufficient for attracting the said armature, but being sufficient, however, to retain such armature in position after having been attracted by its respective electromagnet. In this manner when the magnet 27 is energized from station 1, closing of the switch 11 or 12 in dividing the current between the stations will fail to produce sufficient energization in such an electromagnet as 27₁ to attract its armature, the armature 36 at station 1 being, however, kept in its attracted position. With this construction and this relation of parts, therefore, control from one station automatically locks out the remaining outlying stations.

As already indicated, actuation of the timing wheels a, b, c, d and e from the motor M sets into operation the signalling means or alarm elements g. These alarm elements g are in the form of single stroke gongs. For the purpose of producing or rendering a variety of distinct signals these gongs are operated in the present form of my invention for producing strokes at varying intervals selected at will by the operator at any of the outlying stations. To provide the strokes at intervals a gong circuit is provided which is made and broken at selected intervals. This gong circuit may be traced from the positive terminal of the main line 13 through the lead 14 and switch 15 to the conductor

16 and terminal 17, the said terminal 17 being one terminal of a switch, the other terminal of said switch being designated at 46, the closing of said switch terminals being intended to be effected by the alternate movement of a cross bar 47, the said cross bar 47 being connected to a core 48 forming part of the solenoid S, intermittent operation of the solenoid effecting the alternate movement of the bar 47 for closing the circuit across the terminals 17 and 46, the closing of such circuit effecting the passage of current from the terminal 46 to the conductor 49, thence to a plurality of switches 50 and 51 by way of leads 52 and 53 and from the switches by way of the conductors 54 and 55 respectively to one terminal of each gong, through the gong mechanism and to the other terminal of the gong, thence through the conductors 56 and 57, returning thence through the switches 50 and 51 and to the negative conductor 35 by way of the leads 58 and 59 respectively.

The intermittent energization of the solenoid S for the alternate actuation of the switch bar 47 is effected by means of the timing wheels *a* to *e* inclusive, the operation of these timing wheels being controlled from the outlying stations. For the purpose of operating the gongs in a variety of ways the plurality of timing wheels *a* to *e* are provided, these timing wheels having distinct operating characteristics, any of these timing wheels being intended for selection, depending upon the character of signal desired to be transmitted. The timing wheels are diagrammatically indicated in Figure 1 of the drawings and will be described more in detail hereinafter. For the present purposes it will suffice to state that the timing wheel *a* is adapted to cause the rendition of a signal consisting of a stroke for one second, followed by a silence of three seconds, the timing wheel *b* being intended to cause the rendition of a signal consisting of two successive strokes at intervals of one second followed by a time interval of silence consisting of three seconds, the timing wheels *c*, *d* and *e* effecting the rendition of 3, 4 and 5 successive strokes at intervals of one second, also followed by a time interval of three seconds silence.

Cooperating with the timing wheels *a*, *b*, *c*, *d* and *e* are the make and break contact switches *u*, *v*, *w*, *x* and *y*, each of these switches comprising a stationary contact arm 60 and a movable contact arm 61, the latter arm being actuated by a timing wheel for the making and breaking of a circuit across the contact arms 60 and 61.

For the purpose of selecting the desired timing wheel *a*, *b*, *c*, *d* or *e*, the transmitters T, T₁ and T₂ are provided with selective contact means. These contact means may consist, referring to station 3 in Figure

1 of the drawings, of a stationary arcuate contact means 62 and a plurality of segmental contacts 63, 64, 65, 66, 67 and 68, the contact 63 being dead and comprising therefore the "off" position, the contacts 64 to 68 inclusive being connected by wiring to be described presently for selecting the operation of any of the timing wheels *a* to *e* inclusive. Movable over these stationary contacts is the contact element or arm 69, opposed ends of which span the arcuate contact 62 and any of the selected segmental contacts 63 to 68. The contact element 69 is shown in "off" position in each of the stations 1 to 3.

Assuming that it is desired to select the operation of the timing wheel *e* from station 3, the contact arm 69 will be rotated until the segmental contact 68 is connected to the arcuate element 62, the circuit being traced from the main line 13 under these conditions as follows. The current under operating conditions will flow from the line 13 through switch 15, conductor 16, terminal 17, conductor 18, terminal 19, conductor 20, through lead 22₂ to lead 42₂, through spring arm 39₂, the circuit being closed from said spring arm to contact arm 40₂ when the armature 36₂ is attracted by the magnet 27₂, the current under these circumstances flowing from the contact arm 40₂ to the multiple switch 23₂, thence by way of the conductor 70 to segmental contact 62, across the arm 69 to contact 68, thence through conductor 71, the current flowing from the said conductor back to the multiple switch 23₂ to the lead 72, thence to conductor 73, thence to lead 74 and to the contact arm 60 of make and break switch *y*, the closing of this switch by movement of the arm 61 causing the current to pass to the conductor 75, thence to a cam operated switch *z* comprising a stationary arm 76 and a cam operated movable arm 77, the circuit being completed by the conductor 78 connected to one terminal of the solenoid S, the other terminal of the solenoid being connected to the negative terminal 32. The switch *z* is opened and closed by the rotation of a cam 79, this cam being connected to the motor shafting S, the cam being rotated at the rate of substantially 65 R. P. M., this cam and the switch *z* being provided for the alternate opening and closing of the solenoid circuit in cooperation with the making and breaking of the circuit by means of the timing wheel *e*, as will be further disclosed hereinafter.

From the above it will be understood that upon closing the switch 12 at station 3, not only will the motor be operated and be kept in operation for a predetermined period of time, but the closing of such switch will make ready for selection any of the varying signals, this being accomplished by the actuation of the electromagnetic armature 36₂.

closing the circuit across the automatic switch arms 39₂ and 40₂. It will be further understood that when this takes place the rotation of the transmitter arm 69 may be effected for selecting any of the desired contacts 64 to 68 for selecting any of the desired distinctive signals. The preferable operation or control of the transmitter is first to set the arm 68 in selected position and then to manipulate the switch 12 to set the system into operation. It will be further clear that by this operation the selected timing wheel such as *e* will cause the intermittent energization of the solenoid S in a predetermined manner, this causing the alternate actuation of the switch bar 47 for the alternate opening and closing of the gong circuit in the predetermined manner, the sounding of the alarm thus being obtained.

Although the central control panel P and its operating provisions will effect the sounding of the alarm for a full predetermined period, the operator or officer may discontinue the signals as by shifting the transmitter arm 69 to "off" position, or may change the signal at will by shifting the transmitter arm 69 to any of the other segmental contacts. In the first event, although the motor continues its predetermined operation until stopped by the timing wheel *f*, the sounding of the alarm is discontinued and in the latter event the motor will conclude its predetermined operation with the obtaining of a different signal. With the present system also, the officer need not wait until the completion of the predetermined period of time for resetting the apparatus, since the control elements or instrumentalities at the outlying stations need not be reset to permit control of the central station provisions from any of the other remote or outlying stations. Thus, the transmitter arm 69, after having been set for cooperation with segmental contact 68, may be left in such position, this not interfering with subsequent control of the system from either the stations 1 or 2 or the station 3. The system is thus "fool proof" and eliminates the "human equation."

In a manner similar to the selection of the timing wheel *e* from transmitter contact 68 any of the timing wheels *a*, *b*, *c*, and *d* may be selected from the contacts 64, 65, 66 or 67, the circuits being traced in a manner similar to the above by way of the respective conductors 80, 81, 82 and 83 leading to and through the multiple switches 23₂ to the conductors 84, 85, 86 and 87 respectively, these conductors in turn leading to the switches *u*, *v*, *w* and *x* respectively. Further, in a similar manner the circuits may be controlled from the transmitter switch T and T₁.

Referring to Figures 2 to 4 of the drawings, I show in constructional detail the

central control panel P and the provisions mounted thereon. Attached to the panel P is the electric motor M, the shaft of said motor being provided with the operating worm 88 meshing with a worm wheel 89 fixed to the shaft *s*, the shaft *s* being journalled in opposed bearing brackets 90 and 91 respectively, both being attached in a suitable manner to the panel P. The shaft *s* carries the cam 79, shown more in detail in Figure 3 of the drawings, for operating the make and break device *z*, the shaft *s* being further provided with a worm 92 meshing with a worm wheel 93 fixed to a transverse shaft 94, the latter shaft being journalled in the opposed bearings 91 and 95, the said shaft 94 carrying the timing wheels *a* to *f* inclusive. The gearing is so proportioned that upon actuation of the motor M the cam 79 is rotated at the speed of 65 R. P. M., the said shaft 94 being rotated with a speed of about 1 R. P. M.

In Figure 4 of the drawings the construction of one of the timing wheels such as *e* is shown in detail. This timing wheel *e* is provided with spaced teeth 96 and with intermediate notches or cavities 97, both the teeth and the notches being of a predetermined configuration. In the present case the teeth 96 have a circumferential length so that when a tooth 96 engages the cam block 98 forming part of the spring contact arm 61, the said contact arm 61 will be moved to engagement with contact 60 and will be held in engagement for five consecutive seconds. The notch 97 is of a predetermined length such that when the notch cooperates with the cam block 98 the arm 61 will be released and moved out of engagement with the arm 60 and will be held in released position for the period of three consecutive seconds.

In order to translate the five second period corresponding to the cooperation of tooth 96 with the spring arm 61 into a series of successive make and break contacts in the circuit, the cam wheel 79 hereinbefore referred to is provided, the said cam wheel being shown in detail in Figure 3 as mounted on the shaft *s*, the cam surface of the said cam wheel cooperating with the cam block 99 forming part of the spring contact arm 77, the cam wheel 79 being rotated substantially 65 R. P. M., this cooperating with the timing wheel *e* or any of the other timing wheels to effect the making and breaking of a circuit substantially every second during the period of engagement between a tooth 96 with a cam block 98.

Referring again to Figure 2, the solenoid S is provided with the core 48 hereinbefore mentioned, the said core being connected by means of links 100 to the arms 101 of a bell crank forked lever 102 fulcrumed at 103, the forks of the bell crank defining switch arms

104 and 105 adapted for alternately contacting the terminals 46 and 17 for making and breaking the gong circuit through these contacts when the solenoid S is intermittently energized. For the purpose of limiting the upward motion of the core 48 the solenoid S is provided with a stationary core 104' adjustably mounted on the solenoid by means of the finger wheel 105', the stationary core 104' being provided with limiting stop means 106. The opening of the switch arms 104 and 105 may be effected by the gravity of the parts and for the purpose of aiding the return to open position of the said switch arms I may provide the spring 107 anchored at one end on the frame 108 and connected at its other end to the cross rod 109 connecting the links 100 to the arms 101.

Referring to Figures 5 and 6 of the drawings, I show the preferred form of transmitter embodying the contact mechanism for selective control of the gong circuits and embodying further the switch device for controlling the operation of the motor circuit. The preferred transmitter comprises the casing 110 and the casing cover 111, the said cover being removably mounted on the casing by means of the cooperating spaced lugs 112 and 113, the lugs receiving the securing means such as 114. It is desired to provide a transmitter construction which is air and water proof and to this end I prefer to insert between the casing and casing cover the annular gasket 115. The casing 110 is provided with the aperture 116 through which the connecting wires and leads are led, this aperture being intended to be closed in an air and moisture proof manner.

Fixed to spaced lugs 116' (one of which is shown in Fig. 6) formed preferably integrally with the interior walls of the casing 110 is the insulating plate 117, the said plate carrying the arcuate contact piece 62 and the segmental contacts 63 to 68 inclusive, the said contacts being secured to the insulating plate 117 by any suitable securing means such as screws 118. Each of the contact elements may include a terminal such as 119 and a terminal screw 120.

Secured to the insulating plate 117 I provide the bearing plate 121, the said bearing plate being fixed to the insulating plate by securing means 122. Rotatably mounted in the bearing plate 121 and in the bearing bracket 123, the latter being secured to the casing walls as at 124, I provide the shaft 125.

Insulatably mounted on the shaft 125 and fixed to preferably an integral flange piece 126 of said shaft is the contact arm 69 terminating in the opposed contacts 127 and 128, the latter cooperating with the contacts 62 to 68 inclusive for controlling the selective circuits hereinbefore referred to in detail. The contact element or arm 69 is insulatably mounted on the flange 126 by

means of the insulating bushings 129 and the insulating washers 130 and the securing screws 131. With the provision of these means it will be understood that upon rotation of the shaft 125 the contact arm 69 may be shifted to any selected position.

Rotatably mounted on the casing cover 111 I provide a complementary shaft 132 arranged in alinement with the shaft 125 when the cover is mounted on the casing, as clearly shown in Figure 6 of the drawings, the said shaft being provided with an integral handle 133, the shaft 132 being journalled in the casing cover and being prevented from end-wise movement by means of the shoulder piece 134 and the opposed collar 135. For the purpose of providing a water proof connection between the shaft 132 and the casing cover, the journal for the shaft comprises a stuffing box 136, the cap 137 being provided for gaining access to said stuffing box. For the purpose of operatively connecting the shaft 132 to the shaft 125 when the casing cover is connected to the casing, I provide the shaft 125 with the coupling collar 138, the said coupling collar being provided with a pin 139 projecting therefrom and adapted for reception by a bore 140 provided in the complementary coupling collar 135.

The shaft 134 carries an indicator arm 141, the said arm moving over a series of indications (not shown) on the casing cover 111 for indicating to the operator the position of the contact arm 69. For the purpose of fixedly locating the arm 69 in any of its selected positions I provide the arm 142 fulcrumed on the bearing bracket 123 and to the said arm adjacent its end I connect one terminal of the tension spring 143, the other terminal of the said spring being anchored as at 144 on the bearing bracket 123. The arm 142 carries a roller 145, the said roller being journalled in the arm intermediate its ends, the said roller cooperating with a series of teeth 146 preferably formed in the coupling collar 138, the cooperation of these elements effecting the locking of the switch arm 69 in its selected position. From this construction it will be apparent that the position of the arm 69 may be controlled in a facile manner by the rotation of the handle 133, the parts of the contact mechanism being so related that access may be had to the operating parts thereof in a facile manner when the casing cover 111 is removed from the casing 110.

The transmitter of my construction, in addition to providing a contact mechanism for controlling the signalling operation, preferably also embodies the switch device for controlling the operation of the motor. The switch device designated as 12 may comprise the stationary contact arm 147 mounted on the insulating plate 117 by means of the securing elements 148 and with

this stationary contact arm cooperates a movable spring contact arm 149, the latter comprising a flexible element having a normal position located away from the contact arm 147. For closing the contacts between the arms 149 and 147, I provide the spindle 150 in the form of a plunger, spring controlled, the plunger being slidably mounted in the alined shafts 125 and 134, as clearly shown in Figure 6 of the drawings, one terminal of the plunger being adapted to engage an insulating piece 151 in contact with the switch arm 149, the other terminal of the plunger comprising a push button 152, a spring 153 housed in the handle 133 and surrounding the spindle 150 being provided for normally urging the plunger to open position and for quickly returning the same to open position after the push button 152 is manipulated for closing the circuit across the contacts 147 and 148. For housing the push button and plunger the handle 133 is provided with the cap 154, the cap being secured to the handle by means of screws 155, a flexible diaphragm formed of, for example, animal skin 156 being positioned between the cap 154 and the handle 133, the cooperation of these parts effecting a dust-proof and water-proof construction.

The operation of my improved system will, in the main, be apparent from the detailed description of the system given above with reference to Figure 1 of the drawings. It will be apparent from the construction described that I have provided a system in which a plurality of alarm elements located in various parts of a battleship may be sounded in any of a variety of ways to render any of a plurality of distinctive signals, the operation of the gongs being effected from a central station, the control of the system being obtained from any of a plurality of outlying stations. It will be further apparent that the system can be set into operation instantly by the manipulation of the switch devices 10, 11 or 12, the provisions for operating the signals being set into activity for a predetermined period of time, continued operation of the system being also obtained instantaneously, discontinuance of the signals, however, being obtainable whenever desired by control of the transmitter mechanism at the outlying stations. The system is so furthermore constructed that a signal may be changed at will and that control of the system from one of the outlying stations will prevent interfering control from any of the other stations. The system is, moreover, constructed to permit the operator or officer in charge to abandon control whenever desired without resetting the parts, control from any of the other stations being obtainable, irrespective of the position of the controlling elements at any of the stations, the device thus being rendered

"fool-proof." Moreover, it will be seen that all the elements cooperate in a very simple manner, consistent with the manifold functions involved and that the parts of the system are easily accessible for operation, repair or replacement, the whole providing relatively simple and efficient apparatus.

While I have shown my device in the preferred form, it will be obvious that many changes and modifications may be made in the structure disclosed without departing from the spirit of the invention, defined in the following claims.

I claim:

1. In apparatus of the class described, a signal circuit, a plurality of mechanisms for making and breaking the signal circuit, each with a different arrangement of the relative duration of operation and rest periods, a motor for operating all said make and break connections, a circuit therefor, means operated by the motor for breaking the motor-circuit after the expiration of a predetermined period of operation, a plurality of outlying stations, each including electrically controlled means to select an appropriate make and break mechanism, a circuit therefor, a manually operated switch for closing the motor-circuit, mechanism to short-circuit the selective means and the manually operated switch operated by the current of the motor-circuit, and means operated by the motor-circuit breaking means to short-circuit said last named mechanism just prior to the breaking of the motor-circuit.

2. In apparatus of the class described, a signal circuit, a plurality of mechanisms for making and breaking the signal circuit, each with a different arrangement of the relative duration of operation and rest periods, a motor for operating all of said make and break connections, a circuit therefor, means operated by the motor for breaking the motor circuit after the expiration of a predetermined period of operation, a plurality of outlying stations, each including electrically controlled means to select an appropriate make and break mechanism, a circuit for each of said means, a manually operated switch for closing the motor circuit, mechanism to short-circuit the selective means and the manually operated switch operated by the current of the motor circuit, and means operated by the motor circuit breaking means to short-circuit said last named means just prior to the breaking of the motor circuit, the signal circuit making and breaking mechanisms comprising a circuit, a normally open switch for closing the circuit, and a rotatable member driven by the motor and having means to engage and close the switch at regular intervals.

3. In apparatus of the class described, a signal circuit, a plurality of mechanisms for making and breaking the signal circuit, each

with a different arrangement of the relative duration of operation and rest periods, a motor for operating all said make and break connections, a circuit therefor, means operated by the motor for breaking the motor-circuit after the expiration of a predetermined time, a plurality of outlying stations, electrically controlled means at each station to select an appropriate make and break mechanism, said means being interposed in the motor circuit in parallel, and the current flowing in said circuit of proportions insufficient to operate more than one of said means at one time, a manually operated switch for closing the motor-circuit, mechanism to short-circuit the selective means and the manually operated switch operated by the current of the motor-circuit, and means operated by the motor-circuit breaking means to short-circuit said last named means just prior to the breaking of the motor-circuit; the resistance characteristics of the motor being so selected as to produce a current of a predetermined value in the motor-circuit when the manually operated switch of any outlying station is closed.

4. In a signalling system, provisions for operating a signalling circuit, means for actuating said provisions including an electric motor and a motor circuit, a plurality of outlying mechanisms for controlling the starting of said motor, each electrically operated and including a hand operated switch and a normally open switch device arranged in parallel with the hand operated switch, said normally open switch device including an electromagnet in the motor circuit and arranged to be closed by energization thereof to maintain the motor circuit closed, the current flowing in the motor circuit sufficient to energize the electromagnet of one switch device thereby to hold the circuit closed, but insufficient to simultaneously energize the electromagnet of another switch device.

5. In a signalling system, provisions for operating a signalling circuit, means for actuating said provisions, said means including an electric motor and a motor circuit, a plurality of electrically controlled outlying mechanisms arranged in parallel, each including a normally open switch device for closing the motor circuit, and an electromagnet interposed in the motor circuit, each device arranged to be closed by energization of the appropriate electro magnet to maintain the motor circuit closed, the resistance of the motor and electromagnets being so related to the current value that when a selected magnet is energized, the current will be insufficient to simultaneously energize another magnet, and means controlled by the operation of the motor for opening the motor circuit after a selected period of operation.

6. In a signalling system, provisions for operating a signalling circuit, said provisions having elements adapted for selection to produce any of a plurality of distinctive signals, means for actuating said provisions, the said means including an electric motor and a motor circuit, mechanism for controlling the starting of said motor, the said mechanism including a hand operated switch for closing the circuit, and a normally open switch device for maintaining the circuit closed, said device including an electromagnet in the motor circuit and adapted to be energized by the flow of current in the circuit to operate the switch device, the resistance of the circuit with a selected electromagnet interposed being so related to the current value that the current flow through the selected magnet is sufficient to maintain it closed but insufficient to simultaneously energize another magnet, and make and break contact mechanism for the circuit associated with said provisions for selecting any of its elements.

7. In a centrally controlled signalling system, provisions located at a central station for selectively operating a signalling means to produce any of a plurality of signals, and means for operating said provisions, the provisions including a plurality of means to operate the signalling means, each to produce a different signal, a transmitter located at an outlying station, the transmitter including a manually operated device for selecting the operating means, and manually operated means independent of the device for connecting the operating means with the signalling means and for starting the operating means for the signalling means.

8. In a centrally controlled signalling system, provisions located at a central station for selectively operating a signalling means to produce any of a plurality of signals, a motor for operating said provisions, and a motor circuit, the provisions including a plurality of means for operating the signalling means, each to produce a different signal, a transmitter located at an outlying station, the transmitter including manually selective means for the signal, an independent manually operable switch device for closing the motor circuit, an electromagnet in the circuit, and means operated by the electromagnet for closing the circuit to start the motor and for connecting the appropriate operating means for the signalling means with the selected signal.

9. In a signalling system, an electric controlled signal, a normally open circuit therefor, a solenoid operated switch for closing the circuit, a circuit for the solenoid, a plurality of means to close the solenoid circuit at regular intervals, said means arranged to operate at different intervals thereby to produce a plurality of independent signals,

actuating means for the solenoid circuit closing means, selective mechanism for selecting the circuit closing means, and a make and break mechanism operated by the 5 actuating means interposed in the signal circuit to open and close said circuit at regular intervals during a given period, whereby to provide during each period that the circuit is closed by the solenoid operated 10 switch a series of regular interruptions of the circuit.

10. In a central controlled signalling system, provisions located at a central station adapted for selectively operating a signalling 15 means to produce any of a plurality of signals, the provisions including means to operate the signalling means at different in-

tervals thereby to produce a plurality of distinct signals, means for actuating said provisions, a plurality of transmitters located at outlying stations, each transmitter including means to select any of the signal operating means, and an independent means to operatively connect the signalling means with the selected operating means and to 20 start said actuating means, means to prevent the simultaneous operative connection of another transmitter, and means operated by the actuating means after a selected period of operation for stopping said operation. 25

Signed at New York, in the county of New York and State of New York this 17th day of September, A. D. 1921.

PAUL S. GRIERSON.
